UNITED STATES PATENT OFFICE.

ROMNALD M. FRYDRYCHOWICZ, OF STEVENS POINT, WISCONSIN.

ELECTRIC-SIGN RECEPTACLE.

Specification of Letters Patent. Patented Sept. 25, 1917.

1,241,106.

Application filed January 12, 1917. Serial No. 142,044.

To all whom it may concern:

Be it known that I, ROMNALD M. FRYDRYCHOWICZ, a citizen of the United States, residing at Stevens Point, in the county of Portage, State of Wisconsin, have invented a new and useful Electric-Sign Receptacle; and I do hereby declare the following to be a full, clear, and exact description of the invention, such as will enable others skilled in the art to which it appertains to make and use the same.

This invention pertains to electric light receptacles in general, but is particularly a receptacle for use with electric signs or the like.

15 The principal object of the invention is to provide a receptacle in which the vital parts will be protected from the weather.

20 A second object of the invention is to combine in a device of this character general security and simplicity of structure, and to this end, an outer containing shell is provided in which a pair of lamp bases may be firmly secured.

25 As a third object, the device makes provision for attachment to a conduit carrying electric wires and for the quick and effective attachment of the electrical supply means to their proper contacting points on the lamp bases.

30 Practice may require some changes from the design herein shown, and the right is claimed to make any that do not depart from the spirit of the subjoined claims.

35 The same numerals of reference designate the same parts throughout the several figures of the drawings, wherein:

Figure 1 is a plan view showing the device as a means for carrying the illuminants of an electric sign.

40 Fig. 2 is a side elevation of the receptacle.

Fig. 3 is a sectional view on line 3—3 of

Fig. 2.

Fig. 4 is a sectional view on line 4—4 of

45 Fig. 2.

Fig. 1 shows two signs 1 connected by the channel pieces 2 and having the rods 3 for supporting them on the front of a building or at any other place where the

50 signs may be on display. The conduit 4 carrying the wires 5 supports the receptacle by connecting with its threaded nipple 6.

The lamps 7 are held by the receptacle which also holds the reflectors 8 that are 55 adjustable concentric with the lamps. In Fig. 1 the two reflectors 8 appear in differ-

ent relative positions. This is to show that these reflectors may be positioned so as to obtain the best reflection of the lights 7.

In the receptacle itself, the nipple 6 is 60 integral with the outer containing casing 9, which is adapted to contain the lamp sockets, with the insulating sleeve 10 intervening between them and the outer casing 9. The sockets have the insulating bases 65 11 upon which the shells 14 are held, the shells 14 being adapted to receive the conventional lamp base. One shell 14 carries as integral parts thereof the cylindrical bosses 12 and 13, while the other shell 14 70 carries similarly the cylindrical bosses 15 and 16. Bosses 15 and 16 have threaded holes in their centers and bosses 12 and 13 have similarly disposed body holes for the screws 17. Through their centers the bases 75 11 have the contact studs 18 with their enlarged heads 19 and their bottom portions 20. When the bases are together the two bottom portions 20 form a globular shaped piece with the hole 21 through its center. 80

The nipple 6 has a hole 24 longitudinally through its center and this hole opens into the interior of the casing 9 through the cylindrical projection 22. A hole in the insulating sleeve 10 through which a projection 22 protrudes enables the former to be held in place within the casing 9. On their periphery the bases 11 are counterbored to make room for the projection 22, half of the counterboring being in one base 11 and 90 half in the other. Recesses 25 are formed in the bases 11 which recesses (when the two bases 11 are together) form a continuation of the hole 24. Recesses 23 emanate from recesses 25 and terminate between the 95 bosses 16 and 13. Recesses 23 and 25 with a hole 24 in the nipple provide means for bringing the conducting wires to the connection points on the lamp sockets.

In practice the device is attached by its 100 nipple 6 to any suitable conduit carrying electric conducting wires. The hole 24 then admits the wires into the interior of the casing 9 and the recesses 25 and 23 permit one wire to be clamped at 21 between the 105 two feet 20 and the other to be clamped between the bosses 13 and 16. It will be seen that the screws 17 operate to perform this clamping function, the hole 21 and the space between the bosses 13 and 16 110 being of the proper diameter and width respectively to effectively hold the wires be-

tween them. When the bases are clamped together the counterbored hole in their periphery engages the projection 22 snugly and thus holds them and the socket shells 5 14 which they support firmly in position within the outer casing 9. The method of connecting the conducting wires to the lamp sockets prevents damage to the former from the elements and particularly adapts this 10 device as a receptacle for signs, it being understood that the signs used shall be of any conventional form wherein illuminants are employed to distinguish the lettering.

What is claimed is:—

- 15 1. In an electric sign receptacle, an outer casing having a nipple integral therewith and a projection on its interior where the nipple opens into it, an insulating sleeve adapted to be held in place by engagement 20 with said projection, a pair of lamp sockets similarly secured by said projection, and means for simultaneously securing electric conducting wires to the proper parts of the lamp sockets when securing said lamp sockets in position.
- 25

2. In an electric sign receptacle, an outer casing having a nipple integral therewith and a projection on its interior where the nipple opens into it, an insulating sleeve adapted to be held in place by engagement 30 with said projection, and a pair of lamp sockets similarly secured by said projection, each of said sockets comprising a corrugated cylindrical shell having diametrically disposed cylindrical bosses integral therewith, an insulating base, a central contacting stud and threaded means by which it may be attached to the base of the other socket so that the pair of sockets may be locked in position on the aforesaid projection and clamp electric conducting wires between the contacting studs and the cylindrical boss respectively.

In testimony whereof I have signed my name to this specification in the presence of 45 two subscribing witnesses.

RONALD M. FRYDRYCHOWICZ.
